UNITED STATES PATENT OFFICE.

GEORGE W. GARDNER, OF LA PRAIRIE CENTRE, ILLINOIS.

DESIGN FOR A CEILING.

SPECIFICATION forming part of Design No. 19,295, dated September 3, 1889.

Application filed May 8, 1889. Serial No. 310,061. Term of patent 14 years.

To all whom it may concern:

Be it known that I, GEORGE W. GARDNER, a citizen of the United States, residing at La Prairie Centre, in the county of Marshall and State of Illinois, have invented a new and useful Architectural Design for the Ornamentation of Ceilings, of which the following is a specification.

This invention relates to a new and original architectural design for the surface ornamentation of ceilings, which will be herein-after fully described with reference to the accompanying drawing, which illustrates a plan view of my design, and which represents the ceiling of a rectangular or nearly square room.

My design will be readily understood from the accompanying drawing, by reference to which it will be seen that it consists of the circular stripes C C and D D, the segmental stripes F G II and F² G² II², and the straight stripes f, g, h, and I.

What I claim is—

The surface ornamentation for ceilings shown in the drawing hereto annexed.

In testimony that I claim the foregoing as my own I have hereto affixed my signature in presence of two witnesses.

GEORGE W. GARDNER.

Witnesses:

U. GRANT GARDNER,
WILLIAM MARSHALL.
